William A. Kendall, Winston-Salem, N. C.

Application December 30, 1944, Serial No. 117,167

Term of patent 14 years

(Cl. D44—1)

To all whom it may concern:

Be it known that I, William A. Kendall, a citizen of the United States, residing at Winston-Salem, in the county of Forsyth and State of North Carolina, have invented a new, original, and ornamental Design for a Pressure Cooker or the like, of which the following is a specification, reference being had to the accompanying drawing, forming a part thereof:

In the drawing—

Figure 1 is a view in perspective of a pressure cooker embodying the design in accordance with the present invention; and

Figure 2 is a top plan view of the pressure cooker shown in Figure 1 of the drawing.

I claim:

The ornamental design for a pressure cooker or the like, substantially as shown.

WILLIAM A. KENDALL.
